(57) **CLAIM**

The ornamental design for a neckwear to house and display metallic bars, as shown and described.

DESCRIPTION

FIG. 1 is a front view of a first embodiment of a neckwear to house and display metallic bars showing my new design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a front perspective view thereof;
FIG. 8 is a front view of a second embodiment of the neckwear to house and display metallic bars showing my new design;
FIG. 9 is a rear view thereof;
FIG. 10 is a right side view thereof;
FIG. 11 is a left side view thereof;
FIG. 12 is a top view thereof;
FIG. 13 is a bottom view thereof; and,
FIG. 14 is a front perspective view thereof.

The broken lines depict portions of the neckwear to house and display metallic bars that form no part of the claimed design.

1 Claim, 8 Drawing Sheets
